(57) **CLAIM**

The ornamental design for a rubber foot for musical instrument stands as shown and described.

DESCRIPTION

FIG. 1 is a first perspective view of a rubber foot for musical instrument stands showing my new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash broken lines illustrate portions of the rubber foot for musical instrument stands that form no part of the claimed design. The dot-dash broken lines define the boundary of the claimed design and form no part of the claimed design.

1 Claim, 8 Drawing Sheets
